C. L. BAILEY

CENTRIFUGAL GOVERNOR FOR GASOLINE ENGINES

Filed May 20, 1922

INVENTOR.
Curtis L. Bailey

BY *Chappell & Earl*

ATTORNEYS

UNITED STATES PATENT OFFICE.

CURTIS L. BAILEY, OF LANSING, MICHIGAN, ASSIGNOR TO "NEW WAY" MOTOR COMPANY, OF LANSING, MICHIGAN.

CENTRIFUGAL GOVERNOR FOR GASOLINE ENGINES.

Application filed May 20, 1922. Serial No. 562,490.

To all whom it may concern:

Be it known that I, CURTIS L. BAILEY, a citizen of the United States, residing at Lansing, county of Ingham, State of Michigan, have invented certain new and useful Improvements in Centrifugal Governors for Gasoline Engines, of which the following is a specification.

This invention relates to improvements in 10 centrifugal governors for gasoline engines.

The main object of the invention is to provide an effective structure which can be conveniently adjusted to vary the speed when the engine is running.

15 Further objects, and objects relating to details and economies of construction and operation will definitely appear from the detailed description to follow.

The objects of the invention are accomplished by the devices and means described in the following specification. The invention is clearly defined and pointed out in the claims.

20 A structure which is a preferred embodiment of the invention is clearly illustrated in the accompanying drawing forming a part of this specification, in which:

25 Fig. I is a detail longitudinal sectional view through a governor embodying the features of my invention, taken on the irregular line 1—1 of Figs. II and III.

30 Fig. II is a detail end elevation view, somewhat enlarged, of my improved governor, the connecting rod being broken 35 away.

Fig. III is an enlarged detail longitudinal sectional view through the adjusting means, taken on line 3—3 of Fig. II.

40 In the drawing, the sectional views are taken looking in the direction of the little arrows at the ends of the section lines and similar numerals of reference refer to similar parts throughout the several views.

45 The parts of the drawing will be considered by their numbers. 1 is the governor shell or housing. 2 is the governor shaft. 3 is the gear train to the crank shaft or other moving part of the engine. 4 is a thrust bearing for the governor cross head 5. A 50 pair of weights 6 are fulcrumed at 7 and bearing against the collar 9 of the tension

sleeve 8 by anti-friction rollers 10. 8' is the thrust bearing in the tension sleeve. 11 is the governor lever fulcrumed at 12 and with the end 11' bearing upon thrust collar 13. 14 is the adjustable tension spring acting against the thrust collar and seated at the outer end in the adjusting cap 15. The adjusting cap 15 fits a bearing 15' in the hub-like end of casing 1. The cap 15 has an oblique spiral groove 16 in its periphery. The adjusting cap is retained in position by the pointed screw 17, the point 18 of which engages and projects through the casing into the said spiral groove 16.

60 The adjusting cap is adjustable by the lever 19 which has a projecting arm 20 overhanging the hub and containing a radially disposed spring pin 21, the contact end of which is disposed to engage the notched segment 22 formed integral on the outside of the hub of the casing. 23 is an oil cup for introducing lubricant.

65 It will be readily understood that by adjusting the lever 19 the tension on the spring 14 will be varied and the governor thus adjusted to different resistances and different speeds.

70 Having thus described the invention, what is claimed as new and desired to secure by Letters Patent is:

1. The combination of a centrifugal governor, a suitable casing therefor with an axially projecting hub containing a bearing surface, an adjustable cap with a spiral groove notch in the periphery embracing the governor spindle adapted to and supported in said bearing, a governor spring on the said spindle with its outer end seated in said cap, a pointed screw pin in said hub the point engaging the said groove in the periphery of said cap, a lever for adjusting the said cap, a spring pin carried by said lever, and a notched segment on said hub extension and integral therewith yieldingly engaged by said spring pin, coacting as specified.

75 2. The combination of a centrifugal governor, a suitable casing therefor with an axially projecting hub containing a bearing surface, an adjustable cap with a spiral groove notch in the periphery embracing

the governor spindle adapted to and supported in said bearing, a governor spring on the said spindle with its outer end seated in said cap, a pointed screw pin in said hub

5 the point engaging the said groove in the periphery of said cap, a lever for adjusting the said cap, a spring pin carried by said

lever, and a notched segment on said hub extension yieldingly engaged by said spring pin, coacting as specified.

In witness whereof, I have hereunto set my hand and seal.

CURTIS L. BAILEY. [L.S.]
